CALCULATING MACHINE CASING

Walter A. Anderson, Trumbull, Conn.

Application July 13, 1955, Serial No. 36,967

Term of patent 14 years

(Cl. D64—11)

Fig.2

Fig. 3

Fig. 4

Figure 1 is a side perspective view of a calculating machine casing showing my new design;

Figure 2 is a front elevational view thereof;

Figure 3 is a side elevational view showing the side opposite to Figure 1; and

Figure 4 is a rear elevational view thereof.

I claim:

The ornamental design for a calculating machine casing, as shown.
